(57) CLAIM

The ornamental design for a display holder for CDs or similar objects, as shown.

DESCRIPTION

FIG. 1 is a front perspective view of a display holder for CDs or similar objects showing my new design;

FIG. 2 is a rear perspective view thereof;

FIG. 3 is a side elevation view of one side thereof;

FIG. 4 is a side elevation view of one side thereof;

FIG. 5 is a rear elevation view thereof;

FIG. 6 is a front elevation view thereof; and,

FIG. 7 is a top plan view thereof.

The precise detail of the individual holders at each side in FIGS. 1-4 have not been shown for convenience and ease of illustration. The individual holders shown without precise detail have the same appearance as the holders which are completely shown at the top and bottom of the claimed display holder in FIGS. 1-4 and 7.

The bottom of the display holder for CD's forms no part of the claimed design.

In the figures, the broken line showing of CDs is for illustrative purposes only and forms no part of the claimed design.
